JESSE ALEXANDER, OF BROOKLYN, NEW YORK, ASSIGNOR OF ONE-HALF
TO BERNARD CRONSON, REUBEN CRONSON, AND SOLOMON H. SIEGEL,
OF NEW YORK, N. Y.

TYPE-WRITER RIBBON-MOVEMENT.

SPECIFICATION forming part of Letters Patent No. 761,638, dated June 7, 1904.

Application filed December 29, 1902. Serial No. 137,043. (No model.)

To all whom it may concern:

Be it known that I, JESSE ALEXANDER, a citizen of the United States, residing at Brooklyn, Kings county, New York, have invented 5 certain new and useful Improvements in Type-Writer Ribbon-Movements, of which the following is a full, clear, and exact description.

My invention relates to improvements in type-writers, and particularly to mechanism 10 for effecting the feed of the ribbon by means of which the printing-ink is applied.

The object of this invention is the construction of a mechanism by means of which the ribbon may be fed from side to side of the 15 machine and reversed readily by a single movement by hand when desired. The operation of the feeding is made positive. A construction is also provided by means of which the ribbon is withdrawn from the printing 20 position immediately after the printing of a type and remains withdrawn at all times, except when a type is at the printing position.

The invention consists in providing a system of ratchets and pawls which are operated 25 by means of the type-bar movement for feeding the ribbon and another set of pawls for preventing the backward movement of the ribbon-moving ratchets. Both sets of pawls are controlled by means of a manually-operable reversing-rod, which is accessible on both 30 sides of the machine and which may be adjusted by a simple touch of the hand. The guiding of the ribbon to the printing position is controlled by pivoted guides, which move 35 toward and away from the platen at the instant of printing.

The construction will be more readily understood from the following specification and the accompanying two sheets of drawings, in 40 which—

Figure 1 is a front elevation of those parts of a type-writer embodying the improvements of this invention. Fig. 2 is a side elevation of the same, together with a type and key bar construction for operating it. Fig. 3 is 45 a fragmentary horizontal sectional view and

plan of the left-hand ribbon-moving ratchet and its corresponding operating and holding pawls with the rod for reversing the same.

1 is a universal rock-shaft pivoted in the 50 side frames of the machine and having the upright levers 2 and 3, which are attached to the extensions 4 and 5 from the universal bar 6. This universal bar 6 is situated at the rear of the plate 7, which carries the series of 55 type-bars similar to the type-bar 8. The type-bar 8 is operated by means of the key-bar 9 and intermediate link 10, as shown in Fig. 2.

11 is a spring which is attached to the arm 60 12 and holds the universal bar, shaft, and other attached parts in their normal position.

13 and 14 are the left and right hand ribbon-operating shafts, respectively, through the medium of which the ribbon 15 is moved in 65 one direction or the other. 16 and 17 are the ratchets carried by these ribbon-shafts 13 and 14.

18 and 19 are substantially vertical arms carried by the universal shaft 1 and pivoted at 70 their upper ends to the pawl-bars 20 and 21. These pawl-bars are provided with suitable pawls 22 and 22'. The operation of the universal bar and universal rock-shaft by means of the type-bar mechanism will therefore cause 75 the pawl-bars to be moved forward and backward correspondingly. On the rearward movement the pawl 22 will slip freely over the teeth of the ratchet 16, and on the forward movement if the pawl-bar is in its lowest po- 80 sition it will rotate the ratchet in the direction of the arrow in Fig. 3 anticlockwise. To control the operation of these pawls, I have provided the reversing-rod 23, which is supported at the two opposite sides of the machine in 85 brackets 24 and 25. This rod has at the ends the oppositely-positioned cams 25 and 26. When the rod 23 is in position shown in the drawings, the pawl 22 may engage the teeth 90 of the ratchet 16, and at the same time the cam 26 at the right-hand end of the machine is in such a position as to hold the pawl-bar 21 in

its raised position, so as to hold its pawl 22' out of engagement with its ratchet 17. The movement of the universal bar at such a time, although it causes both pawl-bars to move backward and forward, only operates the left-hand ratchet 16.

To prevent the operating-ratchet from having any tendency to rearward movement when the pawl which is operating it is moving over the teeth of the ratchet, I have provided the pivoted pawls 27 and 28. In the position shown in the drawings the pawl 27 is in engagement with the teeth of the left-hand ratchet 16, so that the said ratchet may be rotated anticlockwise and cannot move backward. At this time the holding-pawl 28 is held in the raised position, as shown in the right hand of Fig. 1, by means of the end of the pawl-bar 21, which is itself raised by means of the cam 26. When the parts are in position shown, it will be noted that the pawl-bar 20 may be raised and fall as the pawl 22 slips over the teeth of the ratchet 16 without moving the holding-pawl 27 or disturbing its operation, except as the pawl itself slips over the teeth of the ratchet on the forward movement. Correspondingly the pawl 28 is not allowed to drop into engagement with the ratchet 17, although the pawl-bar 21 is moved backward and forward.

To reverse the movement of the ribbon and to cause the ribbon to be wound upon the right-hand spool, it is simply necessary to push the reversing-rod 23 to the right, so that the pawl-bar 20 will be raised by the cam 25 and the pawl-bar 21 will be let down by the cam 26, so as to allow the pawl-bar 22' to engage the ratchet 17. At the same time the holding-pawl 27 is raised by the movement of the pawl-bar 20 and the holding-pawl 28 at the right is allowed to drop by the pawl-bar 21.

It will be noted that all of the reversing and holding parts of the mechanism are carried by the two side brackets 24 and 25, so that they may be readily removed from the machine.

At the printing position the ribbon is guided by means of the fingers 29 and 30, which are carried by the guide-block 31. This block is pivotally supported by the pins 32 and 33, carried by the type-bar plate 7. This block 31 also carries the alining devices 35 and 36, by means of which the type is guided to its proper printing position.

37 is a projection carried by the universal bar 6, which is connected to the guide-block 31 by means of the link 38. It will be seen that the movement of the universal bar is transmitted to the block 31 and the alining devices and ribbon-guides 29 and 30. When the type-bar is moved upward, the universal bar is moved to the rear, and thus raises the ribbon 15 upward to the printing position in front of the platen. When the type-bar is released, the spring 11 throws the parts back into position, (shown in Fig. 2,) so that the

printed character is instantly seen by the operator.

The alining mechanism is described and claimed in detail in an accompanying application.

It will be seen that by this simple construction the movement of the ribbon may be readily reversed, so as to be wound upon a spool at either the right or left hand side of the machine, as desired. The construction being of but few parts, it is economical and not likely to become easily disarranged. By combining the alining devices 35 and 36 and the ribbon-guides 29 and 30 into a composite structure which is operated by the same movement the printed matter about the platen is made more readily accessible for reading or purposes of erasures and the like, and these parts are also but little likely to become disarranged. The advantages will be apparent.

What I claim is—

1. A ribbon-moving mechanism for typewriters including a universal rock-shaft, horizontal pawl-bars operated thereby and having horizontal axes, ribbon-moving ratchets adapted to be operated by said pawl-bars, holding-pawls for said ratchets having horizontal pivots, and a reversing-rod for effecting the raising and lowering of the pawl-bars and corresponding holding-pawls.

2. A ribbon-feeding mechanism including a universal rock-shaft, a substantially vertical arm carried thereby, a spring for holding it in its normal position, a substantially horizontal pawl-bar connected to said arm, a horizontally - positioned ribbon - moving ratchet adapted to be moved by said pawl-bar, a holding-pawl adapted to coact with said ratchet the end of said pawl-bar extending underneath a part of said holding-pawl and a cam for lifting or lowering said pawl-bar whereby when said pawl-bar is raised by said cam said holding-pawl is raised and when said pawl-bar is released from said cam said holding-pawl contacts with said ratchet.

3. A ribbon-moving mechanism for a typewriter including a universal rock-shaft, substantially vertical arms carried thereby at opposite ends thereof, a spring for holding said universal shaft in its normal position, substantially horizontal pawl-bars connected to said arms, horizontally - positioned crown-ratchets for moving the ribbon, a holding-pawl for each ratchet, a reversing-rod, cams carried by said reversing-rod, said parts being so positioned that when one pawl-bar is raised by one of said cams its corresponding holding-pawl will be raised and the other pawl-bar with its corresponding holding-pawl will be in operative engagement with its ratchet.

4. A ribbon-moving mechanism for a typewriter including a universal bar, horizontal pawl-bars operated thereby, ribbon-moving ratchets adapted to be operated by said pawl-bars, holding-pawls for each of said ratchets,

reversing-cams for controlling the position of said pawl-bars and said holding-pawls whereby the lifting of one pawl-bar will withdraw its corresponding holding-pawl and the lowering of said pawl-bar will permit the holding-pawl to engage its ratchet.

5. In a type-writer, the ribbon-operating mechanism comprising the combination of a pair of vertical ribbon-moving shafts, crown-ratchets carried by said shafts, a universal bar, a pair of pawl-bars operated thereby resting above and adapted to operate said ratchets, reversing-cams standing beneath said pawl-bars for lifting and allowing them to be lowered, a type-bar plate, a guide-block pivotally mounted thereon, ribbon-guides carried by said block, key and type bar mechanism and means whereby when the type-bar is operated the guide-block and ribbon-guides 20 will be moved backward into printing position and when the type-bar is released the guide will drop forward.

6. In a type-writer, the ribbon-operating mechanism comprising the combination of a pair of vertical ribbon-moving shafts, crown-ratchets carried by said shafts, a universal bar, a pair of pawl-bars operated thereby resting above and adapted to operate said ratchets, a type-bar plate, a guide-block pivotally 25 mounted thereon, ribbon-guides carried by said block, key and type bar mechanism and means whereby when the type-bar is operated the guide-block and ribbon-guides will be moved backward into printing position and when the type-bar is released the guides will drop forward.

7. A ribbon-operating mechanism for a type-writer including a universal bar, a pivotally-mounted guide-block, ribbon-guides 40 carried by said block, a projection from said universal bar, a link connecting said projection with said guide-block, a spring for holding said parts in their normal position whereby when said universal bar is operated said ribbon-guides are thrown backward and when said universal bar is released the spring will operate to move said guides forward and downward for the purpose specified.

8. A type-writer ribbon-operating mechanism including a vertically-mounted type-bar plate, a universal bar mounted at the rear thereof and adapted to be operated by the type-bar mechanism, a pivoted block having a guide for the ribbon and a link pivoted to said block and pivoted to said universal bar at the rear thereof for the purpose specified.

9. A type-writer construction including a pivotally-mounted guide-block, alining devices carried by said block, ribbon-guides carried by said block, mechanism for operating said guide-block toward and away from the printing position, including a universal bar, a link pivoted to the said bar and pivotally connected to said guide-block, and a spring 65 for coacting with said mechanism for nor-

mally holding said guide-block away from the printing position.

10. A type-writer construction including a type-bar plate, a universal bar mounted at the rear thereof, a spring for holding it in its normal position, a pivotally-mounted guide-block, alining-posts carried by said guide-block, ribbon-guides carried by said block and positive connection between said guide-block and said universal bar and key and type bar mechanism whereby the operation of the type-bar upon the universal bar will cause the guide-block and alining and ribbon-guide construction to move upward and backward and the release of the type-bar will cause the said 80 guide-block to move forward and downwardly.

11. A type-writer construction including a type-bar plate, a universal bar mounted at the rear thereof, a spring for holding it in its normal position, a pivotally-mounted guide-block, 85 adjustable alining-posts carried by said block, ribbon-guides carried by said block and positive connection between said guide-block and said universal bar and key and type bar mechanism whereby the operation of the type-bar upon the universal bar will cause the guide-block and alining and ribbon-guide construction to move upward and backward and the release of the type-bar will cause the said 90 guide-block to move forward and downwardly, whereby the type-bar may be guided to the printing position and the alining and guiding device retracted.

12. A ribbon-operating mechanism comprising vertical ribbon-moving shafts, ratchets carried thereby, a vertically-positioned type-bar plate, a universal bar mounted at the rear thereof, key and type bar construction, substantially vertical arms operated by said universal bar, pawl-bars connected to said arms, pawls carried by said bars for engagement with the teeth of said ratchets, holding-pawls for said ratchets, reversing-cams, the said pawl-bars standing underneath said holding-pawls, a pivotally-mounted guide-block, means connected to said universal bar for operating the same, and ribbon-guides carried by said block.

13. A ribbon-operating mechanism comprising vertical ribbon-moving shafts, ratchets carried thereby, a vertically-positioned type-bar plate, a universal bar mounted at the rear thereof, key and type bar construction, substantially vertical arms operated by said universal bar, pawl-bars connected to said arms, pawls carried by said bars for engagement with the teeth of said ratchets, a pivotally-mounted guide-block, means connected to said universal bar for operating the same, and ribbon-guides carried by said block.

14. A ribbon-moving mechanism including a universal bar, ribbon-moving ratchets, pawls having horizontal axes operated by said universal bar, holding-pawls for said ratchets, a

reversing-shaft, cams carried thereby, supporting-posts forming bearings and supports for said shaft and said holding-pawls.

15. A ribbon-moving mechanism including
5 a universal bar, vertically-mounted ribbon-moving shafts, ratchets carried by said shafts, pawl-bars operated by said universal bar, pawls carried thereby for engagement with said ratchets, holding-pawls for said ratchets,
10 a reversing-shaft, cams carried by said shaft beneath and for engaging said pawl-bars, supporting-posts forming bearings for said shaft and carrying the said holding-pawls.

16. A ribbon-moving mechanism including
15 a universal bar, vertically-mounted ribbon-moving shafts, ratchets carried by said shafts,

pawl-bars operated by said universal bar; pawls carried thereby for engagement with said ratchets, holding-pawls for said ratchets, a reversing-shaft, cams carried by said shaft 20 for engaging and lifting said pawl-bars, supporting-posts forming bearings for said shaft and carrying the said holding-pawls, a type-bar plate, a guide-block pivotally mounted thereon, ribbon-guides carried by said block 25 and means for operating said guide, substantially as described.

JESSE ALEXANDER.
